DESIGN FOR A COMBINED MAGAZINE AND BOOK RACK

Peace Love, New York, N. Y.

Application June 18, 1942, Serial No. 107,232

Term of patent 7 years

To all whom it may concern:

Be it known that I, Peace Love, a citizen of the United States, residing at New York, in the county of New York and State of New York, have invented a new, original, and ornamental Design for a Combined Magazine and Book Rack, of which the following is a specification, reference being had to the accompanying drawing, forming a part thereof.

In the drawing:

Fig. 1 is a perspective view of a combined magazine and book rack, showing my new design;

Fig. 2 is a front elevational view;

Fig. 3 is a top plan view; and

Fig. 4 is a bottom plan view of the same.

The design of the combined magazine and book rack opposite to Fig. 1 is the same as illustrated in Fig. 1.

I claim:

The ornamental design for a combined magazine and book rack, as shown and described.

PEACE LOVE.
